THREAD PACKAGE SIZING DEVICE

John F. Mercer, Madison, Ohio, assignor to Industrial Rayon Corporation, Cleveland, Ohio, a corporation of Delaware

Application July 9, 1943, Serial No. 494,024

5 Claims. (Cl. 242—39)

This invention relates to machines for winding material such as thread, cord, filaments, wire and the like, hereinafter referred to as "thread," into package form. The invention provides a new apparatus which stops the operation of the winding machine when the package has reached a predetermined size.

An important advantage of the new thread package sizing device is that it makes possible the production of thread packages of uniform size without any objectionable pressure being exerted against the package in the course of its production. Such pressures frequently cause unevenness in the package being wound and may in some cases damage the thread. The device of this invention is particularly well adapted to be used on the conventional type of package winding machine and may be installed on such machines in a relatively simple manner.

The conventional winding or coning machine is provided with a rotating thread collecting spindle and a frame member which is so constructed and arranged as to recede from the spindle in correspondence with the growth of the thread package being wound thereon. Such machines are also provided with a mechanism for stopping the spindle if the thread being wound thereon should break. This mechanism is usually actuated by a lever which is connected to a member adapted to engage a rotating notched wheel sometimes referred to as a knock-off wheel.

The package sizing device of the invention is advantageously pivoted on this lever of the coning or winding machine and is also connected to the frame member of the machine. The device is so constructed that when the frame member has receded from the spindle a predetermined distance, the device will engage the knockoff wheel and actuate the lever which in turn will cause the spindle-stopping mechanism to function.

The invention will be further illustrated by reference to the accompanying drawings in which Figure 1 represents a front elevation of the device of the invention mounted on a conventional thread-winding machine with parts of this machine being broken away in the interest of clarity; Figure 2 is a side elevation of the device with certain parts broken away; and Figure 3 represents a preferred embodiment of the invention wherein the threaded arm has been given a quarter of a turn to illustrate its structure.

The conventional coning machine shown has a

shaft 10 upon which is mounted a cam (not shown) which operates to reciprocate rod 11 to which is secured thread guide 12. Both the thread guide and the reciprocating rod are supported by a frame member 15 which is pivotally mounted on cam shaft 10 by means of support 16. If desired, the thread guide 12 may be in contact with the thread package 18 which is mounted on the spindle 19 so that the guide 12 and its supporting frame member 15 recede from the spindle 19 as the package grows in size.

The conventional coning machine is also provided with a device which stops the rotation of the spindle when the thread being supplied to the spindle breaks. The thread break stopping device (not shown) may be of the type illustrated in U. S. Patent 801,941 to Wardwell. The device is actuated by raising lever sector 20 which is pivotally mounted on pin 21 and which is provided with detent mean 23 which, upon being released, causes the stopping mechanism to operate. Pivotally mounted on pin 25 of lever 20 is an L-shaped member 26 having arms 27 and 28.

25 In normal operation, the end of arm 28 is kept out of engagement with the rotating knock-off wheel 30 by the thread 31 which passes through the tensioning device 32, past guide pin 33, and through the slotted portion 29 of arm 27 on its way to the reciprocating guide 12. However, when the thread breaks, the L-shaped member 26 rotates about the pin 25 and causes the end of arm 28 to engage the rotating knock-off wheel 30. As a result, lever 20 will be raised 30 and the stopping mechanism will stop the rotation of the spindle 19.

The device of the invention may be mounted at various positions on the lever 20 but advantageously is mounted on the pin 25 which supports the L-shaped member 26. The device comprises a pivoted member 40 one end of which is adapted to engage the rotating knockoff wheel 30. The other end has mounted thereon a yoke 42 which is secured to the member by means of pin 43. The yoke 42 is adapted to fit around the threaded arm 45 which is pivotally mounted at 46 on the lug 47 of frame member 15. The yoke is adjustably positioned around the arm 45 by means of nuts 48.

50 In the operation of this device the pivoted member 40 is in the position shown by the full lines when the package 18 is partially wound. As the package grows in size, until it reaches the predetermined size indicated by the dotted lines at 18A, the frame member 15 recedes with

the growth of the package to the position indicated by the dotted lines at 15A and in so doing moves back with it the threaded arm 45 which is pivotally secured thereto. As a consequence, pivoted member 40 is rotated about pin 25 until it assumes the position indicated by the dotted lines at 40B. As there shown, the free end of the member 40 engages the rotating knockoff wheel 30 and thus causes lever 20 to pivot about pin 21 and actuate the spindle-stopping mechanism.

To permit the production of packages of various predetermined sizes, the yoke 42 may be positioned at appropriate places along the threaded arm 45 by means of the nuts 48. To make a package of relatively small size, the yoke should be advanced toward the free end of the arm 45 whereas the converse would be the case if a larger size package were desired.

Although in the device as illustrated in the drawings the pivoted member 40 and the L-shaped member 26 are both mounted on the pin 25, it is not necessary that the arm be mounted at this particular position on lever 20. Similarly, the pivoted end of the threaded arm 45 need not be mounted on the lug 47 but may be otherwise suitably secured to the frame member 15. In addition, the yoke 42 could be replaced by any other suitable means permitting the positioning of the pivoted member 40 at various places along the threaded arm 45; for example, the arm 45 could be slotted and the end of the arm 40 could be adapted to fit into the appropriate slots necessary to produce a yarn package of the desired size.

I claim:

1. A thread package sizing device for use on a winding machine having a thread-collecting spindle, a knock-off wheel, a lever actuating a mechanism for stopping said spindle, and a frame member so constructed and arranged as to recede from said spindle in correspondence with the growth of a thread package being wound on said spindle, said thread package sizing device comprising means for engaging said knock-off wheel and for actuating said lever when said frame member has receded from said spindle a predetermined distance, said means being connected to said frame member and pivoted on said lever.

2. A thread package sizing device for use on a winding machine having a thread-collecting spindle, a knockoff wheel, a lever actuating a mechanism for stopping said spindle, and a frame member so constructed and arranged as to recede from said spindle in correspondence with the growth of the thread package being wound on said spindle, said thread package sizing device comprising an arm connected to said frame member and a pivoted member pivotally mounted on said lever and secured to

said arm, one end of said pivoted member being so constructed and arranged as to extend from said lever and engage said knockoff wheel when said frame member has receded from said spindle a predetermined distance.

3. A thread package sizing device for use on a winding machine having a thread-collecting spindle, a knockoff wheel, a lever actuating a mechanism for stopping said spindle, and a frame member so constructed and arranged as to recede from said spindle in correspondence with the growth of the thread package being wound on said spindle, said thread package sizing device comprising an arm connected to said frame member and a pivoted member adjustably secured to said arm and pivotally mounted on said lever, one end of said pivoted member being so constructed and arranged as to extend from said lever and engage said knockoff wheel when said frame member has receded from said spindle a predetermined distance.

4. A thread package sizing device for use on a winding machine having a thread-collecting spindle, a knockoff wheel, a lever actuating a mechanism for stopping said spindle, a thread guide adapted to reciprocate longitudinally of said spindle, and a thread guide frame member so constructed and arranged as to recede from said spindle in correspondence with the growth of the thread package being wound on said spindle, said thread package sizing device comprising an arm connected to said frame member and a pivoted member adjustably secured to said arm and pivotally mounted on said lever, one end of said pivoted member being so constructed and arranged as to extend from said lever and engage said knockoff wheel when said frame member has receded from said spindle a predetermined distance.

5. A thread package sizing device for use on a winding machine having a thread-collecting spindle, a knockoff wheel, a lever actuating a mechanism for stopping said spindle, a thread guide adapted to reciprocate longitudinally of said spindle, and a thread guide frame member so constructed and arranged as to recede from said spindle in correspondence with the growth of the thread package being wound on said spindle, said thread package sizing device comprising an arm movably connected to said thread guide frame member, a yoke mounted on said arm, means for adjusting the position of said yoke on said arm, a bar member pivotally secured to said yoke and pivotally mounted on said lever, one end of said bar member being so constructed and arranged as to extend from said lever and engage said knockoff wheel when said frame member has receded from said spindle a predetermined distance.
